N. W. KINNEY

WOOD HEEL MARKER

Filed Sept. 26, 1924

UNITED STATES PATENT OFFICE.

NORTON W. KINNEY, OF HAVERHILL, MASSACHUSETTS, ASSIGNOR TO SLIPPER CITY WOOD HEEL COMPANY, OF HAVERHILL, MASSACHUSETTS, A CORPORATION OF MASSACHUSETTS.

WOOD-HEEL MARKER.

Application filed September 26, 1924. Serial No. 740,060.

This invention relates to marking machines and is herein illustrated as applied to a machine for marking wood heels.

It is customary for the manufacturers of 5 wood heels to mark each heel with various characters, indicating the size of the shoe to which the heel is to be applied, the height of the heel, the style number, etc., as may be found desirable. These marks are usually 10 applied to the concave heel-seat surface of the heel and preferably by means of inked metallic types which are pressed against the heel with sufficient forces to indent the wood and form an impression which is both legible 15 and durable. In order that the impression may be evenly applied to the concave surfaces of the attaching face of the heel, machines of this kind have commonly been arranged so that the type-holder may be 20 adjusted in accordance with variations of the curvature of the attaching face.

In view of the foregoing, an object of 25 the present invention is to provide an improved marking machine suitable for marking wood heels by means of which the character of the work performed may be improved and the quantity increased.

Conforming to this object and in accordance with a feature of the invention, novel 30 mechanism is provided for applying ink to the printing surfaces of the type characters, the mechanism being constructed and arranged to cause an inking-roll to contact properly with the type-faces in whatever position of adjustment they may have been placed. To this end, in the illustrated embodiment of the invention, ink is supplied by means of a felt inking-roll carried at the 35 end of a resiliently positioned arm, which in turn is mounted upon an oscillating carrier arranged to move with a peculiar dipping motion which secures the desired uniform inking of the type-faces.

It will be understood that uniform im- 40 pressions upon the work can only be secured when the heels are held firmly in place in the machine for the application of the printing type. The heel-supporting mechanism for this purpose must, however, be capable 45 of adjustment to coact with any one of

the various styles of heels which may require marking. In accordance with another feature of the invention, therefore, an improved heel-positioning and supporting mechanism is herein illustrated, which, while 55 it does not interfere with the easy and rapid insertion of the pieces of work by the operator, does nevertheless support the work very firmly in the machine and can readily be adjusted for heels of practically any style. 60

A complete understanding of these and other features of the invention may best be had from a consideration of the following specification taken in connection with the accompanying drawing in which:

Fig. 1 is a side elevation of the novel machine;

Fig. 2 is a detail view of the inking-roll carrier, showing it in another position from that in which it is shown in Fig. 1; 70

Fig. 3 is a side elevation of a modified form of heel-positioning and supporting mechanism; and

Fig. 4 is a detail view of one element of the mechanism shown in Fig. 3. 75

Although marking machines of the character under consideration are separate units and may be mounted as such upon suitable bases, it is common to attach them to other machines such, for example, as a wood heel 80 concaving machine, by means of which the concave attaching surfaces of wood heels are scooped out and formed. The marking machine of the present invention has been illustrated as attached to a frame 10 of a 85 concaving machine by means of a bracket 12, upon which there is supported by means of a pivot 14 an oscillating carrier 16 held away from the work by means of a spring 18. The types 20 are gripped in a holder 22 mounted upon an adjustable section 24 of the carrier 16. The position of this section 24 with respect to the body of the carrier 16 is determined in a manner well known in the art by means of a pin 26 entering the 90 hole formed by the coaction of semicircular recesses 27 in the section 24 and the body of the carrier 16. It will be observed that the section 24 is substantially cylindrical and that it is fitted in a correspondingly shaped 100

recess in the carrier 16. By making the spacing of the pin-receiving recesses different in the two parts, a fine adjustment of the position of the types with respect to the carrier 16 may be obtained so that it is possible always to secure parallelism of the type-faces with respect to the impression surface upon the work. Set screws 28 and 30 are provided for securing the section 24 rigidly 10 in the position determined by the pin 26.

To oscillate the carrier 16 toward the work against the force of the spring 18, a frame 30 of the marking device is provided with a detachable guideway 32 in which reciprocates a slide 34 provided with antifriction rolls 36 and 38 at opposite ends. At the end of the guideway 32 away from the carrier 16, another roll 40 is mounted in a suitable carrier which is adjustably positioned 15 by means of a set screw 42 held in place by a lock nut 44. The slide 34 is reciprocated by means of a wedge-shaped cam member 46 mounted at the upper end of a pitman 48 which is pivotally attached at 50 to a rotat- 20 ing part 52 of the concaving machine. The upper end of the wedge-shaped cam 46 is provided with a thin portion designed to guide the main and more rapidly expanding portion between the rolls 38 and 40. This 25 wedge-shaped cam 46 reciprocates the slide 34 and causes the carrier 16 to oscillate against the tension of the spring 18 to make an impression upon the work. At the time of the impression the roll 38 passes the corner of the wedge and bears on the flat portion.

The heel indicated at 54 is supported upon an apertured plate 56 secured to the upper end of the frame 30 and held rigidly in an- 40 gular position by means of a brace 58. A lateral guide plate 60 mounted on the sup- porting plate 56 assists the operator in positioning the heel over the hole in the plate 56. The heel is supported upon the 45 plate 56, so that it will not be moved by the force of the impression of the types, by means of a pillow-block 62 pivotally mounted in an overhanging bracket 64 and capable of adjustment in said bracket by 50 means of set screws 66. The work-contact- ing surface of the block 62 is cushioned with leather. The bracket 64 is capable of longitudinal adjustment upon the supporting plate 56, and its position may be determined 55 by a screw 68. Preferably, the bracket is so positioned that the mark is applied close to the rear end of the concave surface to avoid damaging the mark when the heel is put in a slugging machine to apply the top 60 lift.

In heels of other shapes the slope of the rear surface of the heel may not be sufficient to allow the satisfactory use of the preferred device illustrated in Fig. 1, and in such cases 65 the device illustrated in Figs. 3 and 4 may be

utilized, in which the plate 56 and the lateral guide plate 60 are constructed substan- 70 tially as before but in which an overhanging bracket 70 is provided with a screw 72 hav- ing a lock nut 74 and carrying upon trun- nions 76 and 78, pivotally mounted on a pin 80 in the lower end of the screw 72, a block 82 adapted to engage the tread face of the heel. The block 82 is recessed to re- 75 ceive the trunnions 76 and 78, and flat springs 84 are provided for holding the block on the trunnions. In this arrangement the bracket 70 is adjustable with respect to the plate 56 by means of the screw 68, and in addition an adjustable stop 86 is provided 80 for coaction with the breast of the heel.

Although the machine of the present in- 85 vention may be used without inking the type, it is found that a more legible impression is made if ink is applied regularly to the type- 90 faces, and to this end an ink-saturated, felt roll 90 is pivoted upon the outer end of a finger 92 pivotally carried upon an oscilla- 95 tor 94 by a screw 96. The finger 92 is nor- mally held against a pin 98 upon the os- 100 cillator 94 by means of a spring 100, this pin limiting the movement of the roll toward the type members. Obviously when it con- 105 tacts with the type-faces, it may be moved aside against the tension of the spring. The oscillator 94 is guided for to-and-fro move- 110 ment by means of headed screws 102 and 104 passing through slots 106 and 108 in a guid- 115 ing bracket 110 secured to the under side of the work-supporting plate 56. It will be noted that the upper end of the slot 108 is 120 curved at 112 to cause the inking-roll to be given a dipping movement so that it will contact fairly and firmly with the type-faces regardless of the position of adjustment of the section 24 in the carrier 16. Motion 125 may be transmitted to the oscillator 94 in any desired fashion, but preferably the latter is provided with a hinged finger 114 having an upturned lip 116 in which there is 130 threaded a rod 118 pivotally attached at 135 to the carrier 16.

In the use of the machine, after a piece of work has been placed in position upon the plate 56, the rotation of the part 52 will cause the carrier 16 to be oscillated from the starting position shown in Fig. 1 to a for- 140 ward position in which the type-faces will contact with and be impressed in the at- 145 taching surface of the heel. During this movement of the carrier 16, the oscillator 94 will be retracted toward the bottom of the slots 106 and 108, causing the inking-roll 90 to pass over the type-faces. As the parts 150 return to their initial position, the oscilla- 155 tor will be again drawn toward the upper end of the slots, and the curved end 112 of the upper slot will give to the roll-carrying finger a dipping movement which will in- 160 sure proper contact of the roll 90 with the 165

type-faces whatever may be their position of adjustment in the holder 22 in the carrier 16.

Having thus described the invention, what I claim as new and desire to secure by Letters Patent of the United States is:

1. In a marking machine, a work support, an oscillating type-carrier, means for adjusting the angular position of the type-members with respect to said carrier to vary the impression point with respect to the work support, and means for supplying ink to the type-faces comprising an inking-roll, an oscillator supporting said roll, means for actuating said oscillator, and means for guiding the oscillator constructed and arranged to cause the inking-roll to have a dipping movement to insure proper contact of the roll with the type-faces in any position of adjustment.
2. In a marking machine, a carrier, type-members adjustably supported in said carrier, a fixed guide member, a movable oscillator, a finger mounted on said oscillator provided with an inking-roll resiliently urged toward the type members, a stop on the oscillator limiting the movement of the roll toward the type members, and means for connecting said oscillator to said type-carrier to cause the inking-roll to be drawn across the faces of the type-members as the latter are moved to printing position.
3. In a marking machine, a work support, a slotted guide on said support, an oscillator mounted upon said slotted guide whose movements are determined by said guide, means for reciprocating said oscillator, a stop upon said oscillator, a pivoted finger resiliently held against said stop, an inking-roll carried on said finger, and a printing member movable toward and away from said work support in a path intersecting the path of movement of the inking-roll.
4. In a marking machine, a frame, a work support on said frame, a carrier pivotally supported on said frame, means for actuating said carrier, marking types, a holder for said types mounted upon and angularly adjustable with respect to said carrier to vary their path of approach to the work, inking mechanism supported upon said work support, means for connecting said inking mechanism to said carrier to cause it to be drawn across the printing faces of the types on the carrier, and means for giving said inking mechanism a dipping movement arranged to cause effective contact of the inking device with the printing surfaces of the types in whatever position of adjustment said types may have been placed.
5. In a marking machine, a frame, an oscillating, type-carrying printer in said frame, a work support provided with an aperture to admit the printing device, and means for supporting a wood heel upon said work support comprising a guide plate to

determine the position of the heel and an adjustable pillow-block for engaging and supporting the heel upon the work support.

6. In a marking machine, a frame, an oscillating printing member on said frame, an apertured work-supporting plate arranged to support a wood heel and allow the passage of the printing member so that it will contact with the heel, a lateral guide-plate on said work support, an adjustable bracket on the work-supporting plate, and a pivoted pillow-block in said bracket constructed and arranged to receive and support the overhanging end of a Louis heel.

7. In a marking machine, a support for a Louis heel comprising an apertured plate, means for supporting a heel in contact with said plate comprising a pillow-block adapted to receive and support the overhanging rear portion of the heel, said pillow-block being pivotally mounted for adjustment in accordance with the shape of the heel, and a plurality of adjustable stops for said block.

8. In a marking machine, a frame, an oscillating carrier on said frame, types adjustably supported in said carrier, an apertured work-supporting plate arranged to support a wood heel and allow the passage of the types to contact with the heel, an oscillator, a finger resiliently mounted on said oscillator provided with an inking-roll, means for connecting said oscillator to said type-carrier to cause the inking-roll to be drawn across the faces of the types as the latter are moved into printing position, an adjustable bracket on the work-supporting plate, and a pivoted pillow-block in said bracket constructed and arranged to receive and support the overhanging end of a Louis heel.

9. In a marking machine, a frame, an apertured work-supporting plate on said frame, an oscillating type-carrier mounted on the frame at one side of the work-supporting plate and arranged to imprint a heel positioned on said plate, an adjustable pillow-block and a guide plate on the other side of said work-supporting plate from the type-carrier, a guiding bracket carried by said supporting plate, an oscillator traveling in said guiding bracket, and an inking-roll carried on said oscillator arranged to supply ink to the type-faces of the types of the carrier, said guiding bracket being constructed and arranged to cause the inking-roll to have a dipping movement to insure proper contact of the roll with the type-faces of the types of the carrier.

10. In a marking machine, a frame, an apertured work-supporting plate on said frame, an oscillating type-carrier mounted on the frame at one side of the work-supporting plate and arranged to imprint a piece of work positioned on said plate, a

guide plate on the other side of said work supporting plate from the type carrier, a guiding bracket carried by said supporting plate, an oscillator traveling in said guiding bracket, and an inking roll carried on said oscillator arranged to supply ink to the type faces of types on the carrier, said guiding bracket being constructed and arranged to

cause the inking-roll to have a dipping movement to insure proper contact of the roll with the type faces of the types of the carrier. 10

In testimony whereof I have signed my name to this specification:

NORTON W. KINNEY.
